UNITED STATES PATENT OFFICE.

ALVIN D. SHELDON, OF SANTA MONICA, CALIFORNIA.

CARBURETER.

1,323,919.

Specification of Letters Patent.

Patented Dec. 2, 1919.

Application filed February 6, 1918. Serial No. 215,670.

To all whom it may concern:

Be it known that I, ALVIN D. SHELDON, a citizen of the United States, residing at Santa Monica, in the county of Los Angeles and State of California, have invented new and useful Improvements in Carbureters, of which the following is a specification.

My object is to make an improved carbureter, for internal combustion engines, having means for accumulating and maintaining an air supply to assist in the operation of the carbureter.

Figure 1 is a perspective view of a carbureter embodying the principles of my invention applied to an engine ready for use, parts of the engine being omitted.

Fig. 2 is an enlarged vertical sectional detail on the lines 2—2 of Figs. 1 and 3.

Fig. 3 is a horizontal sectional detail on the line 3—3 of Fig. 2.

Fig. 4 is a perspective view of the graduated air valve plug.

Fig. 5 is an enlarged fragmentary sectional detail on the same plane as Fig. 2, the view being taken on the lines 5—5 of Figs. 3 and 6.

Fig. 6 is a vertical transverse sectional detail on the lines 6—6 of Figs. 2, 3 and 5.

Fig. 7 is a view analogous to Fig. 4 and 30 showing the parts in different positions.

The carbureter casing comprises a flange 1 having bolt holes 2 registering with the bolt holes in the manifold flange 3, and a passage 4 registering with the passage 5 in the manifold. The tubular neck 6 extends downwardly from the flange 1 a considerable distance, and the enlargement 7 extends downwardly from the tube 6. The throttle valve 8 is mounted in the upper part of the tube 6. The air valve casing 9 is formed transversely in the enlargement 7, the float shell 10 extends horizontally from the enlargement 7 substantially on a level with the valve casing 9, and a neck 11 connects the chamber 12 of the shell 10 to the valve casing 9; there being a port 13 through the neck 11 from the chamber 12. A plugged opening 14 is formed in the shell 10 through which the drill is inserted to make the port 13. The float valve construction 15 is mounted in the shell 10. The intake elbow 16 extends downwardly from the enlargement 7. The parts 1, 6, 7, 9, 10, 11 and 16 are all cast integral.

Nipples 17, 18, 19 and 20 extend upwardly from the valve casing 9 in a straight hori-

zontal transverse row. A bore 21 is formed in the valve casing body under the nipples 17, 18, 19 and 20 crosswise of the inner end of the port 13, the end of the bore 21 being closed by a plug 22, so that fuel will flow from the chamber 12 through the port 13 to the bore 21. Vertical bores 23, 24, 25 and 26 are formed downwardly through the nipples 17, 18, 19 and 20 into the bore 21 and smaller bores 27, 28, 29 and 30 are drilled downwardly from the bore 21 through the wall of the valve casing 9 to the valve casing chamber 31, said bores 27, 28, 29 and 30 being centered relative to the bores 23, 24, 25 and 26, and air nozzles 32, 33, 34 and 35 are inserted downwardly through the bores 23, 24, 25 and 26 and driven tightly into the bores 27, 28, 29 and 30, said nozzles extending through the bore 21 and through the bores 23, 24, 25 and 26 and to points above the upper ends of the nipples 17, 18, 19 and 20. Each of the air nozzles 32, 33, 34 and 35 has a tapered upper end 36 and an outlet orifice 37.

The fuel nozzles 38, 39, 40 and 41 are driven tightly upon the nipples 17, 18, 19 and 20, each of said fuel nozzles having a conical upper end 42 and an outlet orifice 43, the outlet orifices 37 and 43 being in vertical alinement and centered relative to each other, so that motor fuel coming from the chamber 12 through the port 13 will fill the bore 21 and rise in the bores 23, 24, 25 and 26 around the air nozzles 32, 33, 34 and 35 nearly to the tips of the air nozzles and establish a level on a line 44 corresponding to the level of the motor fuel in the chamber 12 on the line 45. The normal levels 44 and 45 of the motor fuel may be regulated as desired by regulating the float valve construction 15.

The valve casing bore 31 of the valve casing 9 is tapered and the air valve plug 46 is correspondingly tapered and fits tightly and rotatively in the bore 31. A chamber 47 is formed in the plug, one side of said chamber having a straight longitudinal face 48 and the other side of said chamber having an inclined or winding face 49 the faces 48 and 49 coming together at the point 50 of the plug and being wide apart at the base 51 of the plug. The end face 52 of the plug is squared transversely of the axis and a port 53 leads from the face 52 through the base 51 to the chamber 47. A pintle 54 extends from the point 50 and from the bottom

and small end of the bore 31 through the wall of the casting, and lock nuts 55 are screw-seated upon the pintle 54 outside of the casing against the face 56, so that by manipulating the nuts the plug may be properly tightened in the bore 31 to prevent leakage of air. A crank arm 57 is adjustably fixed upon the outer end of the pintle 54 by a set-screw 58 and an adjusting construction 59 is connected to the other end of the crank arm, the other end of the adjusting construction being connected to a crank arm 60 extending at right angles from the crank arm 61 fixed upon the stem 62 of the throttle valve 8, so that when the throttle valve is operated, the plug 46 is simultaneously operated. The adjustment between the throttle valve 8 and the plug 46 is provided by the adjusting construction 59 and this construction, as shown, consists of a pipe nipple having right and left threads on its ends screwed into hinge members 63 and 64 connected to the hinge pins 65 and 66 carried by the arms 57 and 60.

25 A chamber 67 is formed by making the plug 46 shorter than the bore 31, said chamber 67 being outside of the face 52 of the plug. A cap 68 is secured to the head of the valve casing 9 by cap screws 69, so as to cover the chamber 67, and the air pipe 70 is connected to the cap 68 by a union 71 so as to discharge air into the chamber 67, and the air will pass through the port 53 to the chamber 47 and from the chamber 47 through the uncovered ones of the air nozzles 32, 33, 34 and 35. An air tank 72 is connected to the other end of the air pipe 70, an air pump 73 is connected to be operated by the engine, and a pipe 74 connects the air pump to the air tank 72, so that when the engine is running a constant supply of air is pumped to the tank 72, the supply varying in direct proportion to the speed of the engine. The air nozzles 32, 33, 34 and 35 are all closed by the rotation of the plug 46 bringing the smooth face 75 under the bores 27, 28, 29 and 30. Then as the throttle valve 8 starts to open, the plug 46 will rotate so that the face 49 will pass toward the air valve openings and the opening 30 will first be uncovered to allow air to pass through the nozzle 35, and continued rotation of the plug in the same direction will successively open the nozzles 34, 33 and 32, and the nozzles will open and close in direct proportion to the opening and closing of the throttle 8. The compressed air passing through the nozzles 32, 33, 34 and 35 will produce an atomizer effect to draw the motor fuel out of the fuel nozzles 38, 39, 40 and 41, the motor fuel being thoroughly atomized in this operation.

10 15 20 25 30 35 40 45 50 55 60 65 70 75 80 85 90 95

Various changes may be made in the details of construction without departing from the spirit of my invention as claimed.

I claim:

1. In a carbureter, a valve casing having a tapered bore, a tapered plug in the bore and having a chamber, one side of which is helically positioned upon the face of the plug, a plurality of air nozzles leading from the tapered bore in position to be opened and closed successively by the inclined face of the plug, fuel nozzles mounted around the air nozzles and registering therewith, and means for leading fuel to the fuel nozzles.
2. In a carbureter, a tubular neck forming an air passage having an air intake at its lower end, a valve casing mounted crosswise of the air passage through the tubular neck, said valve casing having a tapered bore, a tapered plug in the bore and having a chamber, one side of which is helically positioned upon the face of the plug, a plurality of air nozzles leading from the tapered bore and discharging upwardly in a row across the air passage, and in position to be opened and closed successively by the inclined face of the plug, fuel nozzles mounted around the air nozzles and registering therewith, and means for leading fuel to the fuel nozzles.

In testimony whereof I have signed my name to this specification.

ALVIN D. SHELDON.
